UNITED STATES PATENT OFFICE.

WALTHER SCHELLENBERG, OF BARMEN-RITTERSHAUSEN, GERMANY.

FURNACE GRATE.

Application filed August 1, 1922. Serial No. 578,994.

To all whom it may concern:

Be it known that I, WALTHER SCHELLENBERG, a citizen of Germany, residing at Barmen-Rittershausen, Germany, have invented 5 certain new and useful Improvements in Furnace Grates, of which the following is a specification.

My invention relates to furnace grates and more especially to grates of the kind in 10 which transverse grate bars provided with openings are arranged in a series in such manner that they form longitudinal passages or channels with slots leading to the furnace.

15 It is an object of the present invention to increase the grate bars in height a little in front of the furnace bridge, the slots formed by these grate bars having a direction opposite to that of the draught of the furnace 20 gases. By this means the introduction of jets of steam and air ordinarily employed in connection with other kinds of grates and acting in the opposite direction to the fuel 25 gases may be readily carried out by making use of grates of the type mentioned provided with transverse grate bars.

The drawings illustrate, by way of example, a form of embodiment of the invention as applied to a double flue boiler, in 30 which

Figure 1 represents an end elevation and Figure 2 represents a longitudinal section.

Figures 3 to 6 show further forms of construction according to the invention in longitudinal or cross-section, respectively.

Referring to the drawings, the grate consists of the usual grate bars *a* arranged in a series transversely to the longitudinal direction of the furnace, the bars forming 40 groups of air passages *b*, whence slots *c*, preferably substantially fan-shaped, lead to the surface of the grate. According to the invention the grate bars near the furnace bridge *d* are so shaped that their upper surfaces rise towards the furnace bridge *d*. The slots *c* in this part of the grate are curved in such a way that the jets or currents of steam or air passing through them are directed away from the furnace bridge, 45 that is oppositely to the direction of flow of the fuel gases.

In order to regulate the admission of the air or steam to the grate, or to enable sections of the grate to be completely closed 55 against the admission of air, control nozzles *f* are provided upon the steam inlet pipe *e*

in front of each passage *b*, and by means of which the quantity of steam or air admitted may be adjusted in accordance with the fuel conditions.

In the construction shown in Figure 3 the grate consists, as in the construction according to Figures 1 and 2, of grate bars *a* arranged in a series transversely to the longitudinal direction of the furnace, the grate 60 bars forming air passages *b*, from which fan-shaped or elongated lanceolate slots extend to the surface of the grate. The upwardly sloping end *f* of the grate, adjacent the furnace bridge *d*, is made in one piece 65 as differentiated from the construction according to Fig. 2, which simplifies very considerably the manufacture and the mounting and removal of this part of the grate. The upwardly directed slots *c* provided in this 70 block *f* are straight. The longitudinal passages of the block *f* are connected by short transverse passages *g*, so that, upon the passage of the air to one or other of the longitudinal passages *b* being interrupted, the 75 rear part of the grate nevertheless received air from the other longitudinal passages along its whole width.

In the construction according to Figure 4 the grate bars are provided with separate 80 passages *d*, through which the air may pass, if in consequence of the energy produced by the current of combustion air passing through the passages *b* the air becomes rarefied and the process of combustion in the 85 forward part of the grate is thus prejudicially influenced. By the arrangement of the passages *d*, which are preferably nozzle-shaped, it becomes possible to regulate the process of combustion in the forward part 90 of the grate to the greatest possible extent.

Figures 5 and 6 show in cross-section and in plan view respectively a special formation of the end *f*² of the grate which is adjacent to the furnace bridge. The grate bars *a*² 100 in this modification are not formed in one piece with the block *f*², but are distinct from the block and are loosely inserted into the block from above. This arrangement has the advantage that it is possible to readily 105 insert and withdraw damaged grate bars without the necessity of disassembling the entire block.

The invention is susceptible of various other modifications and alterations both in 110 the construction as well as in the arrangement of parts in order to adapt the inven-

tion to a variety of different uses and to suit varying operating conditions, and without deviating from the spirit of the invention as set forth and defined in the claims as hereunto appended.

I claim:

1. A furnace comprising a grate and bars forming said grate and extending transversely thereof, said bars having lateral excavations and a plurality of transverse openings, the excavations of contiguous bars forming transverse slots opening into the upper surface of the grate, while the openings of the several bars register with each other and form longitudinal passages extending transversely to and communicating with said slots and a plurality of similar bars increasing in height arranged at the end of said grate, the longitudinal passages in said latter bars being interconnected by transverse passages.
2. A furnace comprising a grate and bars

forming said grate and extending transversely thereof, said bars having lateral excavations and a plurality of transverse openings, the excavations of contiguous bars forming transverse slots opening into the upper surface of the grate, while the openings of the several bars register with each other and form longitudinal passages extending transversely to and communicating with said slots auxiliary ports extending through the bottom portion of said grate into said passages, and a plurality of similar bars increasing in height arranged at the end of said grate, the longitudinal passages in said latter bars being interconnected by transverse passages.

In testimony whereof I affix my signature,

WALTHER SCHELLENBERG.
